Primary Examiner — John Windmuller(74) *Attorney, Agent, or Firm* — Clause Eight IPS; Michael Catania(57) **CLAIM**

The ornamental design for an antenna, as shown and described.

DESCRIPTION

FIG. 1 is a front elevational view of an antenna.

FIG. 2 is a rear elevational view of the antenna of FIG. 1.

FIG. 3 is a top perspective view of the antenna of FIG. 1.

FIG. 4 is a top plan view of the antenna of FIG. 1.

FIG. 5 is a bottom plan view of the antenna of FIG. 1.

FIG. 6 is a side elevational view of the antenna of FIG. 1.

FIG. 7 is an opposing side elevational view of the antenna of FIG. 1.

FIG. 8 is a front elevational view of the antenna of FIG. 1 in use; and,

FIG. 9 is a bottom perspective view of the antenna of FIG. 1 in use.

The broken lines in FIGS. 8 and 9 illustrate environment only and form no part of the claimed design.
